UNITED STATES PATENT OFFICE.

STANISLAW KIELAR, OF MILWAUKEE, WISCONSIN.

RAIL JOINT AND FASTENER.

1,257,083.

Specification of Letters Patent. Patented Feb. 19, 1918.

Application filed September 27, 1917. Serial No. 193,452.

To all whom it may concern:

Be it known that I, STANISLAW KIELAR, a citizen of the United States of America, residing at Milwaukee, in the county of Milwaukee and State of Wisconsin, have invented certain new and useful Improvements in Rail Joints and Fasteners, of which the following is a specification.

This invention relates to certain new and useful improvements in rail joint and fastener.

The primary object of the invention is the provision of a combined fastener and joining means for railway rails whereby the rails are secured in their operative positions upon the ties without the employment of bolts, screws or the usual form of hold fast devices.

A further object of the invention is the provision of a ready and inexpensive means for connecting railway rails to the supporting ties in such a manner that the rails may be quickly detached from the ties when found desirable but being securely attached thereto when operatively positioned.

A still further object of the invention is the provision of a rail fastener formed for coöperation with a tie and arranged with rail engaging parts having detachable interlocking connection with the tie when the rail is operatively positioned upon the latter.

In the drawings forming a part of this application and in which like reference characters designate corresponding parts throughout the several views,

Figure 1 is a vertical longitudinal sectional view taken through a portion of a tie provided with the present device and illustrating a rail in cross section in its secured arrangement, a portion of the tie being shown in side elevation.

Fig. 2 is a horizontal sectional view thereof taken through the webs of the rails.

Fig. 3 is a perspective view of the retaining latch block detached.

Fig. 4 is a side elevation of a portion of a tie illustrating a slightly modified form of the device.

Fig. 5 is a top plan view of the same with a rail shown in horizontal section arranged therein.

Fig. 6 is an inverted perspective view of the abutment block shown in the preferred form of construction.

Fig. 7 is a perspective view of a bed plate employed therewith, and

Fig. 8 is a perspective view of one of the rail engaging plates.

It being understood that the device may be employed for maintaining any form of rails upon suitable supporting ties, the same is herein illustrated in connection with a tie 10 having rails 11 operatively secured thereon. The tie 10 is provided with a notch or seat 12 upon which a bed plate 13 is secured by means of screws 14, the said bed plate being arranged transversely of the tie and adapted to receive the rails 11 longitudinally positioned thereon.

The bed plate 13 is formed with upstanding lugs 15 arranged in pairs adjacent the opposite ends of the plate and adapted for receiving thereover the side notches 16 formed in the base flanges 17 of the rails 11. The notches 16 are arranged at suitable distances from the free ends of the rails 11 for permitting the free ends thereof to be suitably positioned slightly spaced apart when the device is employed as a rail joint, while the notches 16 may be arranged at suitable intervals throughout the length of the rail when the device is employed for securing intermediately positioned ties to the rail for use upon the road bed.

An abutment block 18 is provided for seating within a longitudinal groove 19 of the tie 10 adjacent the seat 12 of the tie with the toe 20 of the block positioned within a socket 21 at the outer end of the groove 19, while an angular bearing plate 22 is carried by the bottom of the block 18 and is provided with a flange 23 for overlying the inner edge 24 of the bottom of the groove 19 for arrangement within a recess 25 positioned in the tie adjacent the cutaway side portion 26 of the bed plate 13. The abutment block 18 is closely fitted within the groove 19 and has a shoulder 27 overlying the bed plate and adapted for engaging the web 28 of the rails 11 while one of the base flanges 17 of each rail projects beneath the shoulder 27.

Spacing plates 29 are mounted upon the opposite sides of the rails 11 having portions 30 for overlying the base flanges 17 thereof and arranged with downwardly projecting lugs 31 positionable within the notches 16 in alinement with the aforementioned lugs 15 of the bed plate it being understood that the spacing plate 29 at one side of the rails is engaged by the abutment block 18.

A retaining latch block 32 is provided for engaging within the tie seat 12 and positioned at the opposite side of the rails from the abutment block 18, a cross piece 33 being arranged upon the bottom of the block 32 and having an inclined outer side 34 for positioning within a groove 35 at the opposite end of the seat 12.

One of the spacing plates 29 will be engaged by the retaining block 32 and with the shoulder portion 36 of such block overlying the adjacent portion of the base flange 17 of the rails 11, when the cross piece 33 is transversely arranged within the seat 12 with the block positioned longitudinally of the tie. The outer sloping end 37 of the block 32 is provided with a latch 38 pivoted within a longitudinal slot 39 thereof as at 40, the said latch being adapted for seating within a keeper slot 41 adjacently positioned within the upper face of the tie 10 beneath the block 32 when operatively arranged. It will be seen that the block 18 in position with the rails 11 may be arranged upon the seat 12 in abutting engagement therewith while the retaining block may then be slidably placed in its position as described with the latch 38 elevated and upon a lowering of the latch within the keeper slot 41, the block 32 will be locked against removal and thereby the entire device will be maintained in its operative arrangement securing the rails 11 upon the tie 10. For detaching the rails, the free end 42 of the latch 38 may be engaged by a suitable instrument and the latch then removed from the slot 41, permitting detachment of the block 32 so that the rails 11 may be separated from the tie 10.

In the form of the device illustrated in Figs. 4 and 5 of the drawings, the same principles of operation are carried out, the tie 10' having a transverse seat 12' for receiving a rail 11'. The abutment block 18' is arranged within a longitudinal groove 19' of the tie and with a shoulder 27' engaging the rail while a plate 22' is carried by the bottom of the block 18' engaging within the bottom of the groove 19'. An oppositely positioned retaining block 32' is provided with a cross piece 33' for arrangement at the opposite end of the seat 12' and having a shoulder 36' overlying the rail.

The retaining block 32' is provided with a latch 38' pivoted within a slot 39' thereof as at 40' and adapted for locking engagement within a slot 41' of the tie, while a lip 42' is provided on the latch for accom-

modating the opening of the latch when it is desired to remove the block 32' for releasing the rail 11'.

It will be seen that a serviceable structure is arranged whereby rails may be firmly connected together mounted upon the ties of the road-bed while the rails may be readily disengaged from the ties when desired.

What I claim as new is:—

1. A rail-holding device comprising a tie having a transverse seat and a longitudinal groove at one side of the seat, an abutment block removably arranged within said groove adapted for engaging one side of the rail, a retaining block adapted for engaging the opposite side of the rail and provided with a crosspiece fitted within said seat adjacent the base flange of the rail and a locking latch swingingly carried by said retaining block adapted for connection with the tie when the device is assembled.

2. In combination with a railway tie having a transverse seat with one inclined end wall and a socket at its opposite end and further provided with a groove extending from the socketed end of the seat and terminating in a recess at its outer end, a rail transversely positioned upon said seat, a retaining block within said groove, retaining means carried by said block extending within the said socket and recess, and with a portion of the block arranged adjacent one side of the rail, a locking block arranged adjacent the opposite side of the rail, a crosspiece carried by said locking block mounted within said seat between the said inclined end wall thereof and the adjacent base flange of the rail and a locking latch swingingly carried by said locking block adapted for engaging the tie when the device is in its operative position.

3. In combination with a tie having a transverse seat, a bed-plate upon said seat, upstanding lugs carried by said plate, rails having side notches adapted for seating upon the said plate with said lugs arranged within the notches, spacing plates engaging the base flanges and webs of the rails arranged with depending lugs positioned within said notches in axial alinement with the lugs of said bed-plate and oppositely positioned removable retaining blocks carried by the tie adapted for engaging the said spacing plates when the device is assembled.

In testimony whereof I affix my signature.

STANISLAW KIELAR.
